A. A. BROWN.
SUPPORT FOR MOPS, BROOMS, FLOOR BRUSHES, AND THE LIKE.
APPLICATION FILED NOV. 3, 1915.

1,182,139.

Patented May 9, 1916.

UNITED STATES PATENT OFFICE.

ARTHUR A. BROWN, OF ST. LOUIS, MISSOURI.

SUPPORT FOR MOPS, BROOMS, FLOOR-BRUSHES, AND THE LIKE.

1,182,139.

Specification of Letters Patent.

Patented May 9, 1916.

Application filed November 3, 1915. Serial No. 59,412.

To all whom it may concern:

Be it known that I, ARTHUR A. BROWN, a citizen of the United States, residing at St. Louis, Missouri, have invented a certain new and useful Improvement in Supports for Mops, Brooms, Floor-Brushes, and the like, of which the following is a full, clear, and exact description, such as will enable others skilled in the art to which it appertains to make and use the same, reference being had to the accompanying drawings, forming part of this specification.

My invention relates generally to mops, brooms, and the like, and more particularly to an attachment which is adapted to be applied to the lower portion of the handle of the mop or broom, and which attachment when properly manipulated will serve as a supporting leg or standard and hold the body of the mop or broom, and particularly the lower portion thereof, elevated from the floor.

It will be understood that when a broom is placed in a standing position upon the floor after use, the weight of said broom tends to bend the straws so that in a short time said straws are permanently curved with the result that to a certain extent, the broom loses its effectiveness in use. Likewise, when a mop is placed in an upright position on the floor after use, the cord or fabric body at the lower end of said mop being wet or moist, frequently discolors the floor or floor covering.

It is the principal object of my invention to overcome the above-stated objectionable results, and to provide a comparatively simple inexpensive attachment which can be readily applied to the handles of brooms, mops, floor brushes, and the like, and which attachment can be manipulated to form a supporting leg which will maintain the brush portion of a broom or the fabric or cord portion of a mop elevated from the floor while said broom or mop is not in use, thereby permitting the straw or brush portion of the broom to maintain its normal straight condition and likewise to prevent the wet portion of the mop from coming in contact with the floor or floor covering and holding said

wet portion in position where it will readily drain into a suitable receptacle.

With the foregoing and other objects in view, my invention consists in certain novel features of construction and arrangement of parts, hereinafter more fully described, claimed, and illustrated in the accompanying drawings, in which—

Figure 1 is an elevational view of a mop, the handle of which is equipped with a suitable support of my improved construction. Fig. 2 is an enlarged cross sectional view taken approximately on the line 2—2 of Fig. 1. Fig. 3 is an elevational view of the lower portion of a mop and showing a modified form of the adjustable support. Fig. 4 is an enlarged section taken approximately on the line 4—4 of Fig. 3. Fig. 5 is an elevational view of the lower portion of a mop and showing a further modified form of the adjustable support. Fig. 6 is an enlarged horizontal section taken approximately on the line 6—6 of Fig. 5. Fig. 7 is an elevational view of the lower portion of a mop and showing a further modified form of the adjustable supporting leg. Fig. 8 is an enlarged horizontal section taken approximately on the line 8—8 of Fig. 7. Fig. 9 is an elevational view of the lower portion of a mop and showing a further modified form of the adjustable support. Fig. 10 is an enlarged horizontal section taken approximately on the line 10—10 of Fig. 9.

In the construction illustrated in Figs. 1 and 2, A designates the mop handle which is usually constructed of wood, and B the fabric or cord body of the mop, said body being secured to the lower end of the handle in any suitable manner. Applied to the lower portion of the handle and preferably on opposite sides thereof are guide rods 10, the ends of which are fixed to the handle A in any suitable manner, and the main body portions of said rods being spaced apart from said handle. In this form of device, the adjustable support is formed of a single length of comparatively stiff wire, the central portion of which is bent to form a substantially U-shaped member 11, which serves as an operating handle and at the ends of

100

the legs of said U-shaped member the wire is bent to form loops 12 which encircle the guide rods 10. From these loops 12, the wire of the supporting member is extended 5 downward to form parallel legs 13, which occupy positions between the handle A and the guide rods 10, said legs extending through that portion of the body of the mop which is secured to the lower end of the handle and the extreme lower ends of said legs being formed into loops 14. When the mop or broom to which this form of device is applied is in use, the handle 11 occupies a position adjacent to the upper ends of the guide rods 10 with the loops 14 on the lower ends of the legs 13 positioned within the body of the mop or broom adjacent to the lower end of handle A. When so positioned, the supporting legs in no wise interfere with the action of the body of the broom or mop 15 as the latter is manipulated in the usual manner. To support the body of the broom or mop above the floor while not in use, the operator engages handle 11 and moves the 20 same downward, consequently moving legs 13 downward through said body, and said mop or broom can now be placed in upright position on the floor with the body of said mop or broom elevated therefrom. When 25 so positioned, the straws of a broom will retain their original condition, and in the case of a mop, the fabric or cord body thereof will be prevented from discoloring the floor or floor covering and the water within said body can readily drain into a suitable receptacle.

In the form of device illustrated in Figs. 3 and 4, a single guide rod 15 is applied to the lower portion of the handle A and the 40 central portion of the wire forming the supporting legs is bent to form a loop 16 which serves as a handle for raising and lowering said legs. At the rear end of this loop 16, the wire is bent to form a pair of oppositely disposed substantially U-shaped bearings 17 which engage on opposite sides of the guide rod 15. From these bearings, the wire is bent to the sides of the handle A and thence downward to form parallel legs 18, 45 the same passing through guide loops 19, which latter are located near the lower end of handle A.

In the form of device illustrated in Figs. 5 and 6, the central portion of the wire 50 which forms the support is bent to form a loop 20 which encircles the handle A and from said loops, the wire is extended forward to form a pair of horizontally disposed substantially U-shaped members 21 which serve as handles in raising and lowering the supporting legs. From the rear lower ends of these handles, the wire extends 55 downward to form parallel legs 22, which occupy positions on opposite sides of the

handle A and these legs operate through 65 suitable guides 23, which latter are fixed to handle A. In this form of device, the loop 20 is intended to grip the handle A with sufficient pressure to maintain the legs in either elevated or lowered positions, and by 70 engaging the outer portions of members 21 and forcing the same toward each other, the loop will be opened a sufficient degree to permit the legs to be moved vertically.

In the form of device illustrated in Figs. 75 7 and 8, the lower portion of handle A is provided with a longitudinally extending groove 24 in which is mounted for sliding movement a single leg 25, the same being provided on its upper end with a projection 80 26 which serves as an operating handle. Clips 27 are positioned on the handle over the lower portion of the groove 24 to retain the leg in operative position and when said leg is drawn upward, its upper end is engaged by a suitable spring catch 28.

In the form of device illustrated in Figs. 9 and 10, the lower portion of the handle is provided with a longitudinally extending slot 29 through which operate legs 30 of the 90 adjustable support, and the central portion of the wire from which these legs are formed is bent to form a horizontally disposed loop 31 which extends partially around the handle.

A device of my improved construction is comparatively simple, can be easily and cheaply manufactured, is readily manipulated and provides simple means for maintaining the bodies of brooms, brushes, mops and the like elevated from the floor when 100 said brooms, brushes, and the like are not in use.

It will be readily understood that minor changes in the size, form and construction 105 of the various parts of my improved device can be made and substituted for those herein shown and described, without departing from the spirit of my invention, the scope of which is set forth in the appended claims. 110

I claim:

1. The combination with a broom or mop handle, of guiding means on the lower portion of said handle, and a leg adapted for movement on said guide and adapted to 115 slide vertically through the central portion of the body of the broom or mop which is carried by said handle.

2. The combination with a broom or mop handle and the broom or mop body carried thereby, of a supporting leg arranged for sliding movement on the lower portion of the handle and adapted to pass vertically through the central portion of the broom or mop body thereon, which leg is greater in 125 length than the body of the broom or mop.

3. The combination with a broom or mop handle and the broom or mop carried there-

by, of a guide rod fixed to the lower portion of the handle and lying parallel therewith, and a supporting leg mounted for sliding movement on said guide rod and adapted to pass vertically through the central portion of the body of the broom or mop.

In testimony whereof I hereunto affix my

signature in the presence of two witnesses this 30th day of October, 1915.

ARTHUR A. BROWN.
